UNITED STATES PATENT OFFICE.

ISAIAH H. TAYLOR, OF PHILADELPHIA, PENNSYLVANIA.

SIFTER OR SCREEN.

No. 798,841.

Specification of Letters Patent.

Patented Sept. 5, 1905.

Application filed January 3, 1905. Serial No. 239,336.

To all whom it may concern:

Be it known that I, ISAIAH H. TAYLOR, a citizen of the United States, residing at Philadelphia, in the county of Philadelphia and 5 State of Pennsylvania, have invented certain new and useful Improvements in Sifters or Screens; and I do hereby declare the following to be a full, clear, and exact description of the invention, such as will enable others 10 skilled in the art to which it appertains to make and use the same.

My invention relates to sifters or screens used for sifting ashes and for other household purposes, and has for its object a device which 15 will prevent the escape of dust arising from ashes being sifted and the thorough separation of the ashes from the unconsumed particles of coal; and the invention consists in certain improvements in construction, which 20 will be fully disclosed in the following specification and claims.

In the accompanying drawings, which form part of this specification, Figure 1 represents a vertical transverse section of an ash-sifter 25 embodying my invention, the parts being exaggerated for the purpose of illustration; and Fig. 2 a top plan view of the receptacle for the material to be sifted.

Reference being had to the drawings and 30 the designating characters thereon, the numeral 1 indicates a sheet-metal can or receptacle and is provided with a bead 2 at its upper end and suitable handles 3, by which it can be carried.

35 4 indicates an inner sheet-metal receptacle, sifter, or sieve for coal or other material to be sifted and is provided with a horizontal flange 5, which rests upon the bead 2 and forms a dust-tight joint therewith, and in the flange 40 is a concentric depression or seat 6, and beyond said seat and forming the extremity of the flange is a gripping-bead 7, designed to be seized by the hands of the person using the device to agitate the contents of the receptacle by imparting semirotary motion thereto. The body of the receptacle 4 is approximately the diameter of the interior of the outer receptacle at a point adjacent to the annular projection 11 to prevent the escape 45 of dust rising in the annular chamber between the two receptacles, and from this point of engagement the body of the receptacle 4 is tapered toward its bottom 8, and the wall 9 is foraminous or perforated, as shown, to afford ready escape for the refuse or ashes.

Sifters of this class as heretofore construct-

ed have been defective in that the mass of coal or ashes in the center of the receptacle or sifter lie inert and receive very little agitation. To overcome this objection, a conical 60 projection 10 is provided on the foraminous bottom 8, and the cone is preferably perforated, as shown, to provide for the escape of fine particles, such as ashes, from the body of the material being agitated as well as from 65 the perimeter thereof.

11 indicates an annular and inward projection in the wall 8 of receptacle 4 for the purpose of arresting dust rising along the wall and for forming a seat for the concentric projection 12 on the cover 13, which seat and projection 12 form the primary or first dust-tight joint between the receptacle 4 and its cover.

14 is a horizontal flange or extension of the 75 cover which terminates in an annular downward-projecting bead 15, which rests in and engages the seat 6 in the flange 5 and forms a supplemental dust-tight joint, and the cover is provided with a handle 16.

17 is an annular chamber around the receptacle 4 into which fine ashes from the perforated wall 9 are discharged and then fall into the receptacle 1.

The several parts of the device are made in 85 the usual manner, the receptacle 4 and the cover 13 being stamped and the projection 11 and the beads 7 and 15 subsequently supplied by suitable beading-machines.

The sifter or sieve thus constructed is as 90 absolutely dust-proof as can be made without the use of gaskets and can be used in any part of a house without the annoyance of escaping dust.

Having thus fully described my invention, 95 what I claim is—

1. A sifter or sieve provided with a tapering perforated wall, an annular inward projection on said wall, and a conical projection on the bottom thereof, and a cover having a 100 downward projection resting on said annular projection.

2. A sifter or sieve provided with a horizontal flange having a depression or seat therein, and a cover provided with a bead at 105 its perimeter engaging said seat.

3. A sifter or sieve having an inward projection on the wall thereof, a flange provided with a depression or seat, and a cover engaging 110 said projection and said seat.

4. A receptacle, a removable sifter or sieve having a horizontal flange engaging the upper

end of said receptacle and provided with a depression or seat and a gripping-bead, and a cover having a bead engaging said seat.

5. An outer receptacle, a sifter or sieve having a body whose greatest diameter is approximately the same as the interior diameter of said receptacle, and tapering downward from its mean diameter and forming an annular chamber between the walls of the two receptacles, a conical projection on the bottom of the sifter, and having a horizontal

flange resting on the upper end of the outer receptacle, said flange having an annular depression or seat therein, and a cover provided with a bead at its perimeter engaging said seat. 15

In testimony whereof I affix my signature in presence of two witnesses.

ISAIAH H. TAYLOR.
